[57] CLAIM

The ornamental design for a combined terminal socket
and casing, as shown and described.

DESCRIPTION

FIG. 1 is a perspective view of the combined terminal
socket and casing therefor showing my new design;
FIG. 2 is a top view thereof;

FIGS. 3, 4 and 5 are respectively rear perspective, front
perspective and front elevational views of the terminal
socket, the casing being omitted for purposes of disclosure;

FIGS. 6 and 7 are respectively front and top perspec-
tive views of the casing, the terminal socket being omitted
for purposes of disclosure;

FIG. 8 is a bottom view of the combined terminal
socket and casing of my design.

FIG. 4.

FIG. 3

FIG. 5.

FIG. 1.

FIG. 2.

FIG. 6

FIG. 7

FIG. 8
